UNITED STATES PATENT OFFICE

2,405,071

PULSE GENERATING SYSTEM

Lewi Tonks, Schenectady, N. Y., assignor to General Electric Company, a corporation of New York

Application October 1, 1943, Serial No. 504,587

11 Claims. (Cl. 171—97)

1

My invention relates to pulse generating systems, particularly to such systems employing spark gaps as a switch mechanism, and has for its object the provision of a new and improved system of this character which produces a pulse once per cycle of a source of alternating potential, operates at a high charging voltage, and supplies a large amount of instantaneous power of constant voltage and with fair timing precision.

In pulse generating systems powered from an alternating current source and using a spark switch it is desirable to have the pulse generating circuit properly disconnected from the alternating current source at the instant of pulse generation to prevent the formation of a power arc across the spark gap. It is also advantageous to generate successive pulses at the same voltage so that the instantaneous power transferred by each pulse shall be the same.

In accordance with my present invention, earlier difficulties are overcome and the foregoing advantages are attained in a simple manner by the provision of a pulse generating apparatus in which a charged capacitive storage element or network is connected to a load by a spark gap arrangement or assembly providing two sparks in series and in which a predetermined initial apportionment of the voltages across the two gaps is changed or disturbed at the desired triggering instant thereby to cause breakdown of the spark gap and to initiate the discharge.

According to my invention, an alternating current source is arranged to charge the storage element through a rectifier, and at a predetermined instant in each cycle of the alternating source voltage the spark gap switch means is triggered by a potential derived from the source, thereby initiating the discharge of the storage element through the load. The capacitive storage element is preferably of such character as to produce a discharge pulse of substantially rectangular wave form. It will be understood that for this purpose, if desired, a suitable section of transmission line may be used. For purposes of illustration, however, I have shown simply a single capacitor as a capacitive storage element.

In one embodiment of my invention, an initial apportionment of voltages across the serially disposed spark gap is disturbed or changed to initiate the discharge by reason of the connection of the intermediate sparking electrode to an intermediate point of a voltage divider connected between points of varying potential in circuit with the alternating current source. By way of

2

example, in circuits where the storage capacitor is charged on alternate half cycles of source potential and triggered on opposite half cycles, I have shown that the triggering voltage divider may be connected either across the transformer secondary winding or across the rectifier connected thereto. In another arrangement where a large auxiliary storage capacitor is maintained permanently charged from one half of a transformer secondary winding the voltage divider may be connected across the other half of the winding.

The novel features which are considered to be characteristic of my invention are set forth with particularity in the appended claims. My invention itself, however, both as to its organization and method of operation, together with further objects and advantages thereof, may best be understood by reference to the following detailed specification taken in conjunction with the accompanying drawing wherein Fig. 1 is a diagrammatic representation of a pulse generating system embodying my invention in one form; Fig. 2 is a graphical representation of certain of the operating characteristics of the pulse generating system of Fig. 1; and Figs. 3 and 4 are diagrammatic representations of pulse generating systems embodying my invention in other forms.

Referring now to the drawing, I have illustrated at Fig. 1 a capacitive storage element 10 arranged to be charged on alternate half cycles from an alternating current source 11 through a charging transformer 12 and a rectifier 13, and to be discharged during the intermediate half cycles of the source potential through a desired output or utilization circuit 15 across which may be connected a suitable leakage resistor or reactor 14. The rectifier 13 may be any suitable unidirectional conducting device and, for purposes of illustration, I have shown a two-electrode electron discharge device of the vacuum or gas-filled type. The utilization apparatus 15 may be any suitable radio apparatus employed to generate high power signals of short duration and accurately timed intervals determined by the frequency of the alternating current source 11. For illustrative purposes, I have shown the apparatus 15 as including a magnetron oscillator upon the anode-cathode circuit of which the pulses from the capacitive element 10 are impressed precisely the frequency of the alternating current source 11 and which is connected to an antenna 16 to transmit therefrom short duration pulses

of intense microwave radiation utilized, for example, in the detection of distant objects.

To discharge the storage element 10 through the load 15, in accordance with the present invention, a switching means is provided comprising a plurality of spark gap members or conductive electrode members 17, 18, and 19. Preferably the electrode members are three in number, as shown in the drawings, thereby to provide two spark gaps 20 and 21 in series between the capacitive storage element 10 and the load element 15. The novel constructional features of the sparking electrodes 17, 18, and 19 are described in detail and claimed in my copending application, Serial No. 432,009, filed February 23, 1942, and assigned to the same assignee as the instant application. For the purpose of fully understanding the instant invention, it is sufficient to note that the electrodes 17, 18, and 19 are suitably supported in predetermined spaced relation and are formed of an electric conducting material. Each electrode is generally elliptical in cross sectional outline, tapering at an angle of approximately 5 degrees from near the axis of the spark gap towards the opposite ends in order to minimize any tendency to form the sparks in other than the line of the axis of the gaps. The electrodes 17 and 18 are provided with axially disposed sparking points formed by rounded rods 22 and 23 mounted in the electrodes 17 and 18, respectively. For cooperation with the points 22 and 23, the electrodes 18 and 19 have formed on those of their faces which cooperate with the rods 22 and 23, respectively, upraised bosses 24 and 25, respectively. To provide for cooling and deionization of the gaps at the termination of a spark discharge, the electrodes 17 and 18 are provided with air ducts 26 and 27, respectively, having inlet connections 28 and 29 at one side of the electrodes and outlet ports 30 and 31 disposed along the arcing axis and concentrically with respect to the rods 22 and 23, respectively. A suitable source of air under pressure (not shown) is connected to the inlet ports 28 and 29. As shown in the drawing the electrodes 17, 18, and 19 are connected in circuit so that the sparking points 22 and 23 are positive with respect to the bosses 24 and 25, respectively.

A triggering potential for the spark gaps 20 and 21 of Fig. 1 is provided by connecting the intermediate electrode 18 to an intermediate point of a voltage divider 33 connected between the terminals of the secondary winding of the charging transformer 12. One terminal of this winding is grounded, and the ungrounded terminal is identified by the reference numeral 35.

Referring now conjointly to Figs. 1 and 2, it will be evident that in operation the condenser 10 is charged from the secondary winding of the transformer 12 through the rectifier 13 on each half cycle of negative potential of the ungrounded terminal 35 of the transformer winding. During this half cycle, no current can flow from the condenser 10 to the load elements 14 and 15 because the spark gaps 20 and 21 are maintained non-conductive, as will be explained hereinafter. During the opposite half cycle of potential, when the point 35 is instantaneously positive with respect to ground, no current can flow through the rectifier 13 to the condenser 10, but during this half cycle the voltage divider 33 acts to initiate a discharge across the spark gaps 20 and 21, thereby to discharge the condenser 10 through the load elements 14, 15.

Accuracy of timing the firing intervals is en-

hanced by irradiating the gaps 20 and 21 from a source of ultraviolet light either continuously or during phases which include at least the firing instants. At Fig. 1 I have shown such a source of ultraviolet light conventionally as a rectangle 36. The source 36 may, for example, be a quartz mercury lamp or a spark in air.

The above pulsing operation will be clarified by referring to Fig. 2. At Fig. 2, the curve E_{35} represents the instantaneous voltage of the transformer terminal 35. This voltage continuously describes a sine wave at the frequency of the alternating current source 11. At the time $t=0$ the voltage E_{35} is shown at the beginning of the negative half cycle. Since the rectifier 13 is conducting during this half cycle, the instantaneous potential of the electrode 19 follows the instantaneous potential of the transformer terminal 35 to its maximum negative value and then, by reason of the unidirectional conductivity characteristic of the rectifier 13, remains at this maximum negative potential until a pulse discharge is initiated. The potential of the electrode 19 is represented by the curve E_{19} at Fig. 2. Furthermore, during the half cycle of negative potential of the transformer terminal 35, the potential of the electrode 18 also describes a negative half cycle by reason of its connection to an intermediate point on the voltage divider 33. Because of its connection to the voltage divider the maximum negative potential of the electrode 18 is less than that of the transformer terminal 35, and this potential is shown by the curve E_{18} of Fig. 2. During this negative half cycle, the potential of the electrode 17 remains tied to ground through the resistor 14, and is indicated on Fig. 2 as E_{17} . Thus, at a time approximately 90 electrical degrees after the time $t=0$, the maximum instantaneous potential of the secondary winding of the transformer 12 exists between the electrodes 17 and 19 across the gaps 20 and 21 in series. This total potential remains across the two gaps in series as the potential of the transformer terminal 35 again approaches zero during the second quarter cycle, the distribution of potential across the two gaps being controlled by the potential of the electrode 18. During this second quarter cycle the potential of the control electrode 18 also approaches zero by reason of the sine wave of voltage applied to it from the voltage divider 33. At a time 180 electrical degrees after the time $t=0$ the full potential of the capacitor 10 is applied across the gap 21 between the electrodes 18 and 19 and the electrodes 17 and 18 are both at zero or ground potential. As the transformer terminal 35 now becomes positive on the positive half cycle of potential of the transformer terminal 35, the potential E_{18} of the electrode 18 also goes positive by reason of the voltage divider connection, thereby to increase the potential across the gap 21 to a value greater than the maximum instantaneous potential of the transformer terminal 35. This gap 21 is so designed that, while it will withstand slightly more than the maximum instantaneous potential of the transformer terminal 35, it will not withstand the scalar sum of the maximum negative transformer potential on the terminal 35 and electrode 19 and the maximum positive potential of the electrode 18 derived from the voltage divider 33 on the positive half cycle. Thus, at some time t_1 , between 180 and 270 electrical degrees after the time $t=0$, the potential between the electrodes 18 and 19 becomes sufficient to break down the gap 21.

At this time the potential E_{18} of the electrode 18 falls substantially instantaneously to the maximum negative potential E_{19} of the electrode 19 because the electrodes 18 and 19 are substantially directly connected by the arc therebetween. This discharge places across the gap 20 alone substantially the full maximum potential of the capacitive storage element 10. The cap 20 is so designed that, while it will withstand the maximum potential applied across it to ground by the voltage divider 33 during the negative half cycle of the transformer potential, it will not withstand the instantaneous potential now applied to it upon discharge across the gap 21. Accordingly, the gap 20 now breaks down and the electrode 17 assumes substantially instantaneously the potential of the electrodes 18 and 19. Thus, at the instant of discharge, the instantaneous potential of all of the electrodes 17, 18, and 19 is substantially equal to the maximum negative potential of the capacitive storage element 10. The condenser 10 now discharges through the gaps 20 and 21 and the load element 15, so that the instantaneous potentials of all three electrodes 17, 18, and 19 decrease toward ground potential as the energy stored in the condenser 10 is gradually exhausted. When the energy of the condenser 10 is exhausted at a time t_2 , the discharge across the gaps 20 and 21 ceases. At this time the electrode 18 is returned substantially instantaneously to control by the voltage divider 33 and its potential again follows the sinusoidal portion of the curve E_{18} of Fig. 2. The potential E_{17} of the electrode 17 remains at ground by reason of its connection through the leakage resistor 14. Similarly, the potential of the electrode 19, having been brought to ground potential by the discharge, remains at ground potential for the remainder of the positive half cycle of transformer potential by reason of the fact that during this half cycle the rectifier 13 is non-conducting and the condenser 10 receives no charge.

In the foregoing explanation it has been assumed by way of simplification that the discharge of the condenser 10 continues until all the electrodes 17, 18, and 19 reach ground potential. In a practical case the discharge may be interrupted shortly before ground potential is reached. In such a case the electrode 18 is returned substantially instantaneously, and at the moment of interruption of the discharge, to control by the voltage divider 33 exactly as in the manner previously described. The potential of the electrode 17, if below ground potential at the instant of arc interruption, is quickly brought to ground potential by leakage discharge through the resistor 14. The potential of the electrode 19 may remain slightly below ground potential, but as soon as the rectifier 13 again becomes conducting on the next negative half cycle the electrode 19 will be connected to the transformer terminal 35 and will follow it in potential in the manner already described.

From the foregoing explanation of the operation of Fig. 1, it will be observed that by this arrangement I am able to initiate an accurately timed pulse of energy through the sparking gaps 20 and 21 once during each complete cycle of the alternating current source 11 and without danger of establishing a power arc from source 11 through the load 15. This operation is carried out with a minimum of apparatus, the discharge being timed from the alternating current source itself by the simple connection of an intermediate

control electrode to a voltage divider connected across the charging winding of the input transformer. In a practical application of the invention constructed and operated in accordance with Fig. 1 using a simulated load, the transformer 12 was connected to a 60 cycle source of alternating potential having a maximum instantaneous value of approximately 30 kilovolts, the voltage divider 33 had a total resistance of 150 megohms, there being 100 megohms between the transformer terminal 35 and the connection of the electrode 18, and the capacitor 10 was of .028 microfarad. With this apparatus, I was able to obtain accurately timed high voltage pulses of a few microseconds duration.

At Fig. 3, I have shown another embodiment of my invention which in many respects is similar to that of Fig. 1, and like parts have been assigned the same reference numerals. At Fig. 20 3, however, the secondary winding of the transformer 12 is provided with a grounded mid tap and terminals 35 and 37 of opposite instantaneous polarity. The transformer 12 of Fig. 3 has connected across one half thereof, in series 25 with the rectifier 13, an auxiliary storage capacitor 40 which is large in relation to the pulse discharge capacitor 10. Across the other half of the secondary winding of the transformer 12 is connected the voltage divider 33, a predetermined 30 intermediate point of which is connected to the control electrode 18. Also, according to the embodiment of Fig. 3, the pulse discharge capacitor 10 is connected across the large capacitor 40 in series with a high resistance resistor 41. The 35 condenser 10 of Fig. 3 may suitably have a capacity of the order of one one-hundredth of the capacity of the condenser 40. Finally, as at Fig. 1, the load elements 14 and 15 are connected across the capacitor 10 in series circuit relation 40 with the two sparking gaps 20 and 21.

The operation of the circuit of Fig. 3 will now be clear from the following brief description. The capacitor 40 is so large that the half wave rectifier 13 is able to maintain the capacitor 40 45 substantially fully charged at all times. Thus, a continuous unidirectional potential is available at the terminals of the condenser 40. Assuming for the purpose of illustration that the spark gaps 20 and 21 are non-conducting at an instant $t=0$, the condenser 10 will now be charged from the condenser 40 to the full unidirectional potential appearing across condenser 40. Let it also be assumed that at this instant the alternating current wave from the source 11 is at its zero point 50 so that the opposite terminals of the secondary winding of the transformer 12 are both at ground potential. At this instant, then, the electrodes 17 and 18 will both be at ground potential and the full voltage of the capacitor 10 will be applied across the gap 21 between the electrodes 18 and 19. If, now, the alternating potential of the source begins a negative half cycle in respect to the transformer winding terminal 35, the opposite terminal 37 of the transformer secondary 55 winding will follow a sine wave of positive potential with respect to ground. As this half cycle proceeds, the potential of the electrode 18 is raised positively by reason of the connection of the voltage divider 33. Thus, the electrode 17 remains at ground potential, the electrode 19 remains at the maximum negative potential of the condensers 10 and 40, and the control electrode 18 is gradually raised above ground potential thereby increasing the potential difference between the electrodes 18 and 19 to an amount

greater than the potential across the condenser 10. At some point less than the maximum positive potential of the electrode 18, the breakdown voltage of the gap 21 will be exceeded. It will be evident that the gap 21 must be set so that it will withstand slightly more than the maximum potential of the condenser 10 but less than the scalar sum of the potential across the condenser 10 plus the maximum positive potential of the electrode 18. The gap 20 may be set for a lesser breakdown voltage, since the maximum voltage applied across the gap 20 is only that portion of the transformer voltage appearing across the voltage divider section between the electrodes 17 and 18. When the gap 21 breaks down, the high negative potential of the electrode 18 is conducted substantially instantaneously to the electrode 10 thereby to place the entire voltage of the condenser 10 across the gap 20 between the electrodes 17 and 18. Since this voltage far exceeds the breakdown potential of the gap 20, the gap 20 will become conducting thereby to establish a discharge path for the condenser 10 through the gaps 20 and 21 and the load element 15 in series circuit relation. After the stored energy in the pulse discharge capacitor 10 has been dissipated in a high current pulse through the gaps 20 and 21 and the load, the large storage capacitor 40 tends to continue the discharge through the resistor 41, the gaps 20 and 21, and the load. However, the resistor 41 is of such large resistance that any discharge current from the condenser 40 alone is small enough to be interrupted by the air blast introduced into the gaps 20 and 21. Thus the arc is interrupted and the gaps 20 and 21 become non-conducting as soon as the condenser 10 is discharged. Thereafter, the condenser 10 recharges from the condenser 40 in preparation for the next pulsing operation.

In a practical embodiment of the apparatus illustrated at Fig. 3, which was tested using a simulated load, the transformer 12 was operated at 60 cycles with a secondary voltage of 40 kilovolts peak. The condenser 40 had a capacity of .06 microfarad, the condenser 10 had a capacitance of 600 micromicrofarads, the resistor 41 had a resistance of 5 megohms, and the voltage divider 33 had a total resistance of 150 megohms, the electrode 18 being connected at a point spaced by 100 megohms from the transformer terminal 37.

At Fig. 4, I have illustrated a still further embodiment of my invention wherein the voltage divider 33 is connected across the rectifier 13 rather than across one of the input transformer windings. In all other respects the circuit of Fig. 4 is similar to that of Fig. 1, and like parts have been assigned the same reference numerals. Although its theory of its operation is not currently fully understood, the circuit of Fig. 4 was tested under simulated load conditions and found to operate quite satisfactorily. In a practical embodiment of the circuit at Fig. 4, the transformer 12 operated at 60 cycles with approximately 8 kilovolts maximum instantaneous potential across the secondary winding, the capacitive element 10 had a capacity of 0.2 microfarad and the voltage divider 33 had a total resistance of 150 megohms, the control electrode 18 being connected to the potentiometer at a point spaced by 50 megohms from the transformer winding terminal 35.

While I have illustrated only certain preferred embodiments of my invention by way of illustration, many further modifications will occur to

those skilled in the art and I therefore wish to have it understood that I intend in the appended claims to cover all such modifications as fall within the true spirit and scope of my invention.

5. What I claim as new and desire to secure by Letters Patent of the United States is:

1. An electric pulse generating system comprising a source of alternating potential, a capacitive storage element, means connecting said capacitive storage element to said source to be charged once per cycle of said alternating potential, a load device, means including a multiple gap spark discharge device for periodically discharging said capacitive storage element through said load device, and voltage dividing means for deriving from said source and impressing across one of said gaps a varying control potential difference which exceeds the breakdown potential of said one gap once per cycle of said alternating potential source thereby to initiate a discharge. 10 15 20 25 30 35 40 45 50 55 60 65 70 75

2. An electric pulse generating system comprising a source of alternating potential, a capacitive storage element, means connecting said capacitive storage element to said source to be charged once per cycle of said alternating potential, a load device, means including a multiple gap spark discharge device for periodically discharging said capacitive storage element through said load device, said capacitive storage element when charged impressing across said gaps in series the total potential of said capacitive storage element, and voltage dividing means for deriving from said source and applying to said discharge device a potential such that at a predetermined time after said capacitive storage element becomes fully charged the potential difference across one of said gaps exceeds said maximum charging potential thereby to initiate a discharge of said storage element through said gaps and said load device.

3. An electric pulse generating system comprising a source of alternating potential, a capacitive storage element, means connecting said capacitive storage element to said source to be charged once per cycle of said alternating potential, a load device, at least three spaced electrodes providing two spark gaps in series between said capacitive storage element and said load device, voltage dividing means for impressing upon an intermediate sparking electrode at least a portion of said alternating potential thereby to initiate a discharge of said capacitive storage element through said load device once per cycle of said alternating potential, and means for irradiating said gaps with ultraviolet light at least during the intervals of cyclic discharges.

4. An electric pulse generating system comprising a source of alternating potential, a capacitive storage element, means including a unidirectional conducting device for connecting said capacitive storage element to said source to be charged to a predetermined maximum instantaneous potential once per cycle of said alternating potential, a load device, three spaced electrodes defining two spark gaps in series between said capacitive storage element and said load device, and voltage dividing means for deriving from said source and applying to the intermediate of said three electrodes a potential such that the total potential difference between said intermediate electrode and one other of said electrodes exceeds said predetermined maximum instantaneous potential of said capacitive storage device once per cycle of said alternating potential there-

by to initiate a discharge of said storage element through said load device.

5. An electric pulse generating system comprising a source of alternating potential, a capacitive storage element, means including a unidirectional conducting device for connecting said capacitive storage element to be charged from said source once per cycle of said alternating potential, a load device, a multiple gap spark discharge device comprising at least three spaced electrodes defining two spark gaps in series between said capacitive storage element and said load device, and voltage dividing means associated with said source potential and having an intermediate point connected to an intermediate electrode of said spark discharge device thereby to initiate once per cycle of said source potential a discharge of said capacitive storage element through said load device.

6. An electric pulse generating system comprising a source of alternating potential, a capacitive storage element, means including a unidirectional conducting device for connecting said capacitive storage element to said source to be charged once per cycle of said alternating potential, a load device, a multiple gap spark discharge device comprising at least three spaced electrodes defining two spark gaps in series between said capacitive storage element and said load device, and voltage dividing means connected directly across said source of alternating potential and having an intermediate point connected to an intermediate electrode of said spark discharge device thereby to initiate once per cycle of said alternating potential a discharge of said capacitive storage element through said load device.

7. An electric pulse generating system comprising a source of alternating potential, a capacitive storage element, means including a unidirectional conducting device for connecting said capacitive storage element to said source to be charged once per cycle of said alternating potential, a load device, a multiple gap spark discharge device comprising at least three spaced electrodes defining two spark gaps in series between said capacitive storage element and said load device, and voltage dividing means connected directly across said unidirectional conducting device and having an intermediate point connected to an intermediate electrode of said spark discharge device thereby to initiate once per cycle of said alternating potential a discharge of said capacitive storage element through said load device.

8. An electric pulse generating system comprising a source of alternating potential, a first capacitive storage element, means including unidirectional conducting means for maintaining said first capacitive storage element charged from said source to a predetermined substantially constant unidirectional potential, a second capacitive storage element connected to be charged from said first capacitive storage element through an impedance device, a load device, means including a multiple gap spark discharge device for periodically discharging said second capacitive storage element through said load device, and voltage dividing means for deriving from said source and applying across at least one of said gaps a control potential difference varying with time and arranged to initiate a discharge of said second capacitive storage de-

vice through said load device once per cycle of said alternating potential.

9. An electric pulse generating system comprising a source of alternating potential, a first capacitive storage element, means including a unidirectional conducting device for connecting said first capacitive storage element to be maintained continuously charged from said source to a predetermined substantially constant unidirectional potential, a second capacitive storage element connected to be charged through a high impedance device from said first capacitive storage element, a load device, a plurality of spaced electrodes defining at least two spark gaps in series between said second capacitive storage element and said load device, voltage dividing means for deriving a potential proportional to the potential of said source and applying said derived potential across one of said gaps thereby periodically to initiate a discharge of said second capacitive storage element through said load device, and means for interrupting said discharge upon dissipation of the energy of said second capacitive storage device.

10. An electric pulse generating system comprising a source of alternating potential, a first capacitive storage element, means including a unidirectional conducting device for connecting said first capacitive storage element to said source to be maintained continuously charged to a substantially constant unidirectional potential, a second capacitive storage element connected to be charged through an impedance device from said first capacitive storage element, a load device, three spaced electrodes defining therebetween two spark gaps in series circuit relation between said second capacitive storage element and said load device, the full unidirectional potential of said first capacitive storage element being applied across said gaps in series when said gaps are non-conducting, and voltage dividing means for deriving from said source and applying to one of said electrodes a varying control potential such that once per cycle of said alternating potential the potential difference across one of said gaps exceeds said constant potential thereby to initiate a discharge of said second capacitive storage element through said load device.

11. An electric pulse generating system comprising a source of alternating potential, a first capacitive storage element, means including a rectifier for connecting said first capacitive element to said source to be maintained continuously charged to a substantially constant unidirectional potential, a second capacitive storage element connected to be charged through an impedance device from said first capacitive storage element, a load device, three spaced electrodes defining therebetween two spark gaps in series circuit relation between said second capacitive storage element and said load device, means for deriving an alternating potential of opposite phase with respect to said source potential, and voltage dividing means associated with said potential of opposite phase and having an intermediate point connected to the intermediate of said three electrodes thereby to initiate a discharge of said second capacitive storage element through said load device once per cycle of said source potential.

LEWI TONKS.
